DESIGN FOR A SILENT BUTLER

Wade E. Ballard, Los Angeles, Calif., assignor to Modern Plastic Co., Los Angeles, Calif., a partnership

Application January 26, 1946, Serial No. 125,992

Term of patent 7 years

(Cl. D85—5)

To all whom it may concern:

Be it known that I, Wade E. Ballard, a citizen of the United States, residing at Los Angeles, in the county of Los Angeles, State of California, have invented a new, original, and ornamental Design for a Silent Butler, of which the following is a specification, reference being had to the accompanying drawings, forming part thereof.

Figure 1 is a perspective view of the silent butler embodying my new design.

Fig. 2 is a top plan view of the same.

Fig. 3 is a view in front elevation of the same.
Fig. 4 is a view in side elevation of the same.
Fig. 5 is a bottom plan view of the silent butler embodying my new design.

Fig. 6 is a rear view in elevation of the same.

I claim:

The ornamental design for a silent butler, as shown.

WADE E. BALLARD.
